CLAIM

The ornamental design for a surface ornamentation for the sides of a shoe midsole, as shown and described.

DESCRIPTION

FIG. 1 is a left side elevational view of surface ornamentation for the sides of a shoe midsole showing my new design; and

FIG. 2 is a right side elevational view thereof.

The broken line showing of a shoe in FIGS. 1 and 2 is for illustrative purposes only and forms no part of the claimed design.

FIG. 2
